UNITED STATES PATENT OFFICE.

CHARLES S. PHILIPS, OF BROOKLYN, NEW YORK.

IMPROVEMENT IN PROCESSES OF TREATING TOBACCO.

Specification forming part of Letters Patent No. **222,530**, dated December 9, 1879; application filed February 4, 1879.

To all whom it may concern:

Be it known that I, CHARLES S. PHILIPS, of Brooklyn, in the county of Kings and State of New York, have invented a new and Improved Process of Treating Tobacco, of which the following is a specification.

My invention relates to a new process of imparting to tobacco ammoniacal vapors, and has for its object the neutralizing in the tobacco of certain objectionable odors, which are created in the tobacco when it is exposed to a high degree of heat, either moist or dry.

The color of tobacco used for manufacturing cigars has become a matter of much study and attention, as less tobacco of a dark color is grown than is sufficient to meet the wants of commerce and manufacturers. This has been the cause of making many devices for giving a dark color to tobacco by exposing it to a high temperature, whereby a darker color will be developed. This proceeding is accompanied with generating in the tobacco a very objectionable odor, which bad odor will adhere to the tobacco and impair its value. Many devices for removing the said odor have failed.

I have discovered that by exposing the tobacco to the action of the vapors of ammonia the aforesaid bad odor is thoroughly overcome, and the tobacco will have as natural and good a flavor as if it had not gone through any treatment which would affect its good odor or quality.

I have further discovered that the tobacco will readily absorb, and that its constituent bodies will combine with the aforesaid ammoniacal vapors, whereby whatever ammoniacal properties the tobacco originally contained, but lost during its treatment, are replaced.

In carrying out my invention I use an apartment in size according to the amount of tobacco to be treated and sufficiently air-tight to prevent the escape of the ammonia vapors. The tobacco is placed therein in such a manner that the ammonia vapors arising from below find access to all parts of the tobacco. I therefore place the tobacco on racks or shelves which are a little separated from each other, or I hang it up.

For evaporating the ammonia I use the ordinary aqua-ammonia of commerce. I rely on the action which the air has on it and place it in shallow pans, and place these pans on the floor underneath the tobacco in various parts of the aforesaid air-tight room or apartment. The nature of ammonia is such that it will spontaneously pass into vapor, which rises and penetrates the tobacco. A few hours will suffice to bring about the desired result. The tobacco is then ready for use or to be packed for future use.

I do not broadly claim the application of ammonia to tobacco, as it is a well-known fact that ammonia is very much used by adding it to the water used for wetting or moistening the tobacco preparatory to fermenting or sweating the same; but the ammonia so used is decomposed and driven out of the tobacco during a forced sweat by high heat, thus doing no good. Ammonia so used leaves a salty deposit on the leaf, which gives to cigars a grayish mold-like appearance, while ammonia vapors have no objectionable features.

I am aware that ammonia has been used in the same way and for the same purpose, but in connection with other materials or ingredients, and also diffused through tobacco during the artificial sweating process, which occurs at a temperature of about 200° Fahrenheit; but it is dissipated by the heat to a very great degree, if not altogether; hence I apply the ammonia after the sweating process.

Having thus described my invention, I claim as new and desire to secure by Letters Patent—

A process of curing tobacco for smoking purposes, that consists in sweating the leaf under a high and moist temperature until it assumes a dark color, and then applying ammoniacal vapor until the empyreumatic odor is removed.

CHARLES S. PHILIPS.
